APPARATUS FOR WEAVING TERRY FABRIC

Marc Van de Castele, Roubaix, France

Application May 10, 1935, Serial No. 20,866
In France May 12, 1934

6 Claims. (Cl. 139—26)

This invention has for its object improvements in processes for weaving looped tissues, more particularly terry fabrics. The invention is characterized by a device for the regulation of the opening forming the loop, so that the consumption of loop warp, which depends primarily upon the size of the opening, is always exactly in agreement with the predetermined loop warp feed, which will permit of applying to this warp a constant tension by means of an oscillating back beam counterbalanced by weights.

The length of loop warp supplied with respect to a length of basic warp woven is called "loss" and this definite feed of looped warp is obtained by a continuous distribution only operated under the tension of this warp.

The invention furthermore permits of weaving parts of the fabric without loops, without adjustment, and of recommencing automatically the manufacture of the looped fabric without any irregularity.

The accompanying drawing shows diagrammatically the application of the invention to a loom with a hinged connecting rod, Figure 1 illustrating a method of forming a looped fabric, and Figure 2 being a detail view, partly in section, of a device connecting the feed roller with the draft cylinder.

Figure 3 shows an arrangement of the members permitting the automatic regulation of the opening which forms the object of the invention.

To facilitate the understanding of the drawing, each of the spindles fixed to the frame of the machine is indicated by a cross hatched round spot.

In weaving looped terry fabrics or the like, one method consists in inserting, for example, the two weft threads 1 and 2 of Figure 1 at a certain distance from the weft thread 4 previously inserted, and then a third weft thread 3 which will be beaten up against the fabric already made at the same time as the weft threads 1 and 2. On doing this, these three weft threads, in which the looped warp threads 5 are interlaced and to a certain extent held, will slide on the base warp which is kept tight, carrying with them the less tensioned loop threads, which will form, according to their interlacing, loops at the front or at the back of the fabric.

The term "opening" means that space which is temporarily left between the fabric already made and the weft threads 1 and 2, and it will be easily understood that this is the principal factor determining the length of the loops, although the

tension of the loop warp also has an important influence.

For a like opening, the stronger the tension of the loop warp the shorter the loops, for there will be produced a greater backward sliding on the weft threads which hold them. This sliding cannot be eliminated by reducing the tension of the loop warps since the knots are then not formed at the back of the loops, but it cannot become too large since it then becomes irregular and the loops are not uniform in length although their mean length may be that which is desired.

It will therefore be seen that a suitable and constant tension of the loop warp is important for obtaining a good looped fabric. From what has been explained of the action of the tension of the loop warp, it may be stated that the length of the loops is approximately inversely proportional to the tension of its warp and approximately directly proportional to the size of the

A third factor also has an influence, namely, the tension of the base warp, for the greater this is, the tighter will the loop threads be held, thus increasing the force of the interlacing of these with the weft threads which carry them along.

The size of the loops is, therefore, also approximately directly proportional to the tension of the base warp and variations in the latter arising from the reduction of the diameter of the wound warp or from imperfections of braking will alter the length of the loops even in the case of a loop warp kept under a constant tension.

Furthermore, although the opening may be made constant from the mechanical point of view, it is not so from the point of view of efficiency with respect to the formation of the loops, for the following reasons:

It is known that in fabrics well supplied with threads and particularly with weft threads, these weft threads are not moved into their final position at the first stroke of the lay which inserts them. There is a certain return of the fabric towards the back of the loom which is termed "repulse" or "backing", so that the following strokes of the lay have a further compressing effect upon the weft threads already inserted until equilibrium is established with the forward movement of the fabric carried by the draft cylinder; nevertheless, this "backing" exists with each stroke of the lay in closely woven tissues and obviously results in reducing the opening mechanically obtained.

Thus, any variation of the "backing" will cause

a variation of the actual opening and consequently of the length of the loops. Now, though this "backing" depends upon the number of weft threads, it also depends upon the size of these and upon the facility of insertion thereof, due, for example, to their surface roughness, which roughness may vary according to the different treatments necessitated by the bleaching, dyeing or other operations.

Thus, all these properties of the weft will also influence the size of the effective opening.

In order nevertheless to obtain a regular "loss," feed cylinders have been employed giving a definite length of feed of the loop warp. The tension of this warp thus depends upon the difference between the size of the effective opening and the length supplied, which is necessarily less in order to maintain a tension in the loop warp.

In this case, the unavoidable variations of the effective opening will cause a corresponding variation in the tension of the loop warp which will then not have the constancy and the proper value which is so important, as shown above. The invention has therefore sought to deal with the problem in another manner and, since a perfect looped fabric requires both a definite feed of loop warp and a constant tension in the latter capable of easy regulation, it is proposed to act on the causes of these variations of tension, that is to say, principally on the variations of the effective opening which determines a greater or less draft of the loop warp.

The devices which characterize the present invention have for their object to eliminate all the causes of irregularity by creating an automatic regulation of the "loss" of loops combined with the tension of the loop warp, the tension of the base warp, and the facility of inserting the weft by acting automatically on the size of the opening. In the particular case where it is desired to manufacture a certain length of fabric without loops, a special device acts automatically on the feed of the loop warp.

These devices comprise:

(a) A device controlling and limiting the feed of the loop warp and

(b) A regulating device varying the size of the opening in such manner that it is always in proper relation to the length of loop warp supplied, and also acting on the tension applied to this warp and even, to a certain extent, on the tension of the base warp.

The feed cylinder for the loop warp comprises lightly braked warp beam 6, on which this warp is wound, and a feed roller 7 covered with felt or similar frictional material in such manner that there should be no slipping.

The roller does not cause the movement but is itself moved by the tension applied to the loop warp without, however, being able to exceed a definite ratio of rotation.

To this end, this roller 7 is mechanically connected with the cylinder 8 for drawing the woven fabric, through a transmission the ratio of which may be regulated by changing the pinion 9, in such manner that to a particular amount of fabric wound up there corresponds a particular feed quantity of loop warp. The number of teeth on the pinion 9 may be determined according to the length of the loop warp supplied, with respect to the length of the base warp, that is to say, to the "loss" of loop warp.

The particular feature of this connection resides in the fact that one of the transmission pinions 75 is freely rotatable in one direction, that is to

say, that if there were no draft of the loop warp, there would be no rotation of the roller 7, as shown by Figure 2.

The rotation of the roller 7 only occurs due to the tension applied to the loop warp by the back beam 10 which is itself supported by a lever 11 counterbalanced by one or more weights 12 which are adjustable in position so as to regulate the tension of the loop warp and to obtain, after regulation, a constant tension on this warp. The lever 11 may, as shown, be mounted to oscillate about the axis of the roller 7.

The opening regulator is controlled by the displacement of the back beam roller 10 and, consequently, of the lever 11 which is connected to a part 13 forming a sliding shoe and having a groove 14 in which moves, with a certain amount of play, a block 15 hinged to a lever 16.

A variation in the position of this block causes a variation of the inclination of the lever and this inclination is transmitted by connecting rods 17 to a lever 18, pivoted about a point 19, thus altering the position of a pawl 20 which is adapted to engage the pivot pin 21 and thus modify, as is already known, the effective length of a connecting rod 22 by flexing this connecting rod into two parts 22 and 23. The pawl 20, by means of the rod 38 and the lever 37, obtains from the suitable cam 36 the movement which will cause its engagement with the pivot pin 21. In the ratio of 3 shots per loop for example, this cam 36 keyed on the shaft 35 will make one revolution for three of the crank-shaft, the pawl will engage during two revolutions and will be disengaged at the third; thus, the lay will insert two weft threads with opening and at the third will beat up all the three against the fabric already made, thus forming loops.

The variation in size of the opening is thus obtained by the forward and backward movement of the shaft 31 carrying the pawl 20.

Furthermore, when the pawl 20 engages the pivot 21, the effort required for the flexing of the connecting rod drawn back by the spring 29 exerts on this pawl a tractive effect which is arranged to be greater than the contrary action of the spring 30 drawing back the lever 18 and the shaft 31 towards the rear of the loom. On the engagement, the block 15 thus moves in the slot of the sliding shoe and comes to bear on a different surface, and on the disengagement, the spring 30 brings the block back to its first position.

It will furthermore be seen that the engagement of the pivot 21 tends to diminish the opening, since it draws the pawl forward, and that the disengagement tends to increase it since the spring 30 draws it back.

These two contrary tendencies are controlled by the position of the sliding shoe which follows the position of the back beam 10 without effort or reaction, since the play of the block in the slot 14 permits on each engagement and disengagement, a reciprocating movement of this block, which momentarily liberates the sliding shoe.

If, for example, the opening becomes too large, the consumption of loop warp will become greater than its feed, the back beam and the sliding shoe will descend and the opening will diminish until equilibrium is established between the consumption and the feed of the warp.

If the tension of the loop warp were increased, there would also be an increase in the opening to 75.

compensate for the greater slip which would take place in the formation of the loops.

In the same way, if the tension of the base warp were reduced and if the wefting were altered for a similar difference of length between the loop warp and the base warp, there would be a different number of loops, and thus a change of length of these and an automatic correction of the opening.

10 As in the manufacture of terry fabrics, for example, it is necessary to make parts of the fabric without loops by means, for example, of the Jacquard or pattern mechanism, the pawl 40 is caused to engage the end 39 of the lever 37 at the moment when the latter is in the position shown on the drawing.

At this moment, the pawl 20 not being in engagement, the action of the spring 30 is no longer counterbalanced by that of the spring 29 drawing 20 the connecting rods, as shown on the drawing, and the block 15 no longer disengages periodically the sliding shoe 13 which is kept fixed between its guides 33.

Since there is no longer any formation of loops, 25 the back beam commences to move upwards; but the sliding shoe 13 cannot follow it especially since the adhesion of the block 15 in the slot 14 is increased by a fine serration made in the surfaces of the groove and on the sides of the block 30 and there results a strong pull on the rod 25 which, through the lever 26 hinged at 27 on the lever 11, causes the brake 28 to act.

At this moment, the loose pinion in the transmission from the draft cylinder comes into operation 35 and permits the roller 7, which is braked, only to supply the length of warp necessary for the weaving of the portion without loops.

At the moment of recommencing the looped weave, the sliding shoe is again dropped at each 40 engagement of the pawl 20 with the pivot 21, and the back beam 10 is thus liberated. The brake is released and the roller 7 resumes its normal unwinding for supplying the loop warp.

The consecutive weaving of portions of the 45 fabric with and without loops does not necessitate a coupling taking up the pinion 34, since the length of loop warp not consumed in making the fabric without loops, is not fed by the roller 7 which is then braked and this under-consumption 50 need not be transferred to the fabric with loops since the "loss" is calculated with respect to the fabric with loops and not with respect to the whole of the parts with and without loops.

The external portion of the loose wheel shown 55 in Figure 2 receives its impulse from the roller 7, whilst the inner part is given a definite movement from the cylinder 8 drawing the fabric.

It will be seen by the arrangement of the pawls that the exterior of the free wheel can 60 rotate less quickly than the interior when the roller 7 is braked, and at the same speed when this roller is not braked, but never more quickly.

There is thus obtained an absolutely automatic regulation of the opening and of the supply 65 of looped warp and consequently an absolutely regular working without it being necessary to regulate from time to time the opening with respect to the tension of the various warps, even in the case of modification of the weft or of 70 the prime materials employed.

Naturally the shapes and the details of construction and arrangement may be varied without departing from the scope of the present invention which applies equally to other systems 75 also known in the weaving industry for obtain-

ing the opening necessary for the manufacture of looped tissues, such as movable frames or reeds.

I claim:

1. In combination with a loom for weaving looped fabrics, particularly terry fabrics, means 5 for continuously supplying loop warps, means for taking up the fabric woven in the loom, means controlled by said take-up means for determining the maximum length of feed of the loop warps, means for applying tension to said loop warps and means controlled from said tension-applying means for varying the stroke of the loom lay.

2. A device for the automatic regulation of the opening forming the loops in looms for weaving 15 looped fabrics, comprising in combination with a roller off which the loop warp is unwound, a movable back beam carried by levers counterbalanced by adjustable weights and having the loop warp passed therearound, variations in the 20 traction of this warp arising from variations in consumption thereof being adapted to cause an alteration in the position of the back beam, a sliding shoe connected to control means adapted to effect a variation in the size of the opening, 25 and means for transmitting the variation in the position of the back beam to the said sliding shoe.

3. In combination with a loom of the character described, a device regulating the opening forming the loops in the loom for weaving looped 30 fabrics, comprising a back beam, hinged levers having said back beam mounted thereon, a sliding shoe having the motion of said back beam transmitted thereto by connection through said hinged levers, a block rotating about an axis, 35 said sliding shoe having a slot formed therein acting on said block, pawls mechanically connected to said block, said pawls retaining the lay of the loom, articulated connecting rods connecting said sliding shoe with said pawls, and said 40 sliding shoe modifying the position of said pawls for regulating the size of the opening by any alteration in the position of said shoe.

4. A device for the automatic regulation of the opening forming the loops in looms for weaving 45 looped fabrics, comprising in combination with a roller off which the loop warp is unwound, a movable back beam carried by levers counterbalanced by adjustable weights and having the loop warp passed therearound, variations in the 50 traction of this warp arising from variations in consumption thereof being adapted to cause an alteration in the position of the back beam, a sliding shoe connected to control means adapted to effect a variation in the size of the opening, 55 braking means secured to the back-beam levers adapted to control the movement of the loop warp roller, and a rod connecting said braking means with the sliding shoe, whereby a movement of the back beam upwardly brakes the 60 warp roller against the weight of the sliding shoe, through the intermediary of the connecting rod, said shoe releasing the brake whenever the back beam moves downwardly.

5. In a device as claimed in claim 4, a gear 65 train between the loom driving means and the loop warp roller driving means, said gear train having a ratchet differential clutch whereby said clutch is inoperative whenever the loop warp roller speed equals that of the loom driving means, 70 said clutch operating to add a tension on said warp when the consumption is high to cause oscillation of the back beam and releasing said tension when weaving fabric without loops.

6. In a loom of the character described, means 75

for transmitting oscillations of a back-beam to the loop regulating means of a terry fabric loom, comprising a rod co-operating with the back-beam, a sliding shoe having a notched edge cam opening, a member movable in said opening and having corresponding notches, an oscillating lever secured at one end to the movable member, a second lever connected to said first lever and

movable therewith, and limiting means formed on the lay, a hook actuated by the second lever and adapted for engagement with said limiting means so as to limit the movement of the lay in correspondence to that of the back-beam through 5 the instrumentality of the sliding shoe and co-operating levers.

MARC VAN DE CASTEELE.
